WINDOW SCREEN

Nelson B. Joyner, Huntington, W. Va.

Application July 31, 1941, Serial No. 404,946

4 Claims. (Cl. 160—25)

This invention relates to a novel construction of window screen for windows having sliding sashes, and more particularly to a window screen which, when not in use, will be contained in a recess of the window frame so as to be protected from the elements and not to obstruct the window opening.

More particularly, it is an aim of the invention to provide clamping means associated with the outer edges of the top and bottom rails of the sliding sash and which are connected to means manually operable from one side of said sash for opening and closing said clamping members so that said clamping members may be engaged with or disengaged from the free ends of strips of mesh wire fabric which are wound on spring rollers and which extend into the top and bottom of the window opening and in positions to be received by the open clamping members when the sash is at the extremities of its movement.

Still a further aim of the invention is to provide a construction whereby the side edges of the strips of mesh wire fabric will extend into slots in the stiles or perpendicular guides of the sash, when said strips are extended, so that the strips will completely close the parts of the window opening in which they are disposed, when in extended positions.

Still another aim of the invention is to provide means for latching the clamping members in either open or closed positions so that, when in open positions, the sash can be moved in either direction to the extremity of its movement without the free ends of either strip of mesh wire fabric being engaged by either of the clamping members. Other objects and advantages of the invention will hereinafter become more fully apparent from the following description of the drawings, which illustrate a preferred embodiment thereof, and wherein—

Figure 1 is a side elevational view looking toward the inner side of the window and with portions of the window frame shown broken away and in section.

Figure 2 is a top plan view of the same with the top panel of the window frame removed.

Figure 3 is a transverse vertical sectional view taken substantially along the plane of the line 3—3 of Figure 1.

Figure 4 is a horizontal sectional view of the same taken substantially along the plane of the line 4—4 of Figure 1.

Figure 5 is a bottom plan view taken substan-

tially along a plane indicated by the line 5—5 of Figure 1.

Figure 6 is a detail vertical sectional view taken substantially along a plane indicated by the line 6—6 of Figure 1.

Figure 7 is an enlarged edge view in elevation of the lower, inner sash,

Figure 8 is a front elevational view of the same looking toward the inner side thereof and partly in vertical section,

Figures 9 and 10 are vertical transverse sectional views of portions of the bottom rail of said sash taken substantially along planes indicated by the lines 9—9 and 10—10, respectively, of Figure 8.

Referring more particularly to the drawings, wherein like reference characters designate like or corresponding parts throughout the different views, 10 designates generally a conventional construction of window including a frame, designated generally 11 and having a head 12, sill 13 and stiles 14 which combine to form the window opening 15 in which is slidably mounted a lower sash 16 and an upper sash 17, in a conventional manner. The upper, outer sash 17 is of conventional construction and is supported in a conventional manner in a raised position by means of sash weights 18 through the medium of sash cords 19 which are attached to the weights 18 and the sash 17 and which are trained over rollers 20. The parts 18, 19 and 20 are disposed in the recesses of the stiles 14 with the corresponding upper ends of the sash cords 19 extending into the window opening 15. The head 12 and sill 13 are recessed to form chambers 21 and 22, respectively, and the remote ends of the head 12 and sill 13 are provided with removable panels 23 to afford access to the chambers 21 and 22. The inner sides of the head and sill are provided with elongated slot-like openings 24 and 25, respectively, which open into the upper and lower ends, respectively, of the window opening 15 and which are substantially wider than the window opening.

Each of the chambers 21 and 22 contains a pair of roller supporting brackets including a bracket 26 and bracket 27. Each of the pairs of brackets 26 and 27 is adapted to support a conventional spring roller 28, in a conventional manner and so that when the roller is turned in one direction its spring will be tensioned to cause it to rewind. A strip or sheet of mesh wire fabric 29 is wound on each of the rollers 28. The strips 29 are provided with free ends which project through the slots 24 and 25 and into the upper

and lower ends, respectively, of the window opening 15.

The side panels 39 which form the inner sides of the stiles 14 are provided with corresponding longitudinally extending slots 39' in the ends thereof and in the portion thereof which is slidably engaged by the lower, inner sash 16. The slots 39' communicate at their remote ends with the ends of the slot-like openings 24 and 25 and terminate in spaced apart relationship to one another at their adjacent ends, as seen in Figure 3. The free ends of the mesh wire fabric strips 29 extend through the slot-like openings 24 and 25 and into the upper and lower ends of the frame opening 15 and the sides or longitudinal edges of the strips 29 extend into the slots 39', as seen in Figure 1, due to the fact that the strips 29 are substantially wider than the opening 15. The free end of the upper strip 29 is wrapped around and fastened to a rod 31 and the free end of the lower strip 29 is similarly attached to a rod 32 which rods are longer than the openings 24 and 25 so that their ends extend beyond the ends thereof to prevent said rods from being drawn through the openings 24 and 25 and into the chambers 21 and 22, respectively. The strips 29 are wrapped on the rollers 28 so that the spring tension of the rollers tends to wind the strips 29 thereon and to draw the free ends thereof inwardly of the chambers 21 and 22 so that the ends of the rods 31 and 32 form stops for limiting this movement of the strips 29.

The rollers 28 are preferably not provided with latch means so that they are constantly sprung urged to wind the strips 29 thereon.

Referring particularly to Figures 7 to 10, the lower, inner sash 16 includes a bottom rail 33 and a top rail 34 which rails are provided with channels 35 in their outer longitudinal edges so that the bottom rail 33 is provided with a downwardly opening channel 35 and the top rail 34 has an upwardly opening channel 35. The channels 35 extend the length of the rails 33 and 34.

A clamping member 36 is disposed in and extends substantially the length of the channel 35 of rail 33 and a similar clamping member 37 is disposed in a like manner in the channel 35 of the rail 34. Clamping members 36 and 37 each comprise sections 38 and 39 which are substantially semi-circular in cross section so that the clamping members when closed, as seen in Figures 7, 9 and 10 are substantially tubular in shape. The sections 38, of the clamping members, are fixedly secured in the channels 35 by fastenings 40 which engage the rails 33 and 34.

Referring to Figure 8, the bottom rail 33 is provided with a centrally disposed recess 41 containing a lining 42 of suitable material such as metal. Recess 41 opens outwardly of the inner side of the rail 33 and is adapted to be normally closed by means of a door 43 which is hinged at one end thereof to the inner side of the rail 33. As shown in Figure 8, the rail 33 at each end thereof is provided with a recess 44 and a recess 45. Recesses 45 are disposed above the complementary recesses 44. The ends of the lining 42 are provided with openings 46 which communicate with the recesses 44 and openings 47 which communicate with the recesses 45. A shaft 48 extends through the recess 41 and is loosely disposed near its ends in the openings 46 and has its ends extending into the recesses 44. A shaft 49, similar to the shaft 48 is disposed thereabove and loosely disposed in the openings 47 and has its ends extending into the recesses 45.

The perpendicular side rails of the sash 16, designated 50, and the ends of the rails 33 and 34 are recessed, as seen in Figures 7 and 8. Said recesses include elongated recesses 51 which extend into the ends of the rail 33 and shorter recesses 52 which extend into the ends of the rail 34. The recesses 44 and 45 open into the recesses 51 at their remote ends and said remote ends are normally closed by means of plates 53 which are disposed in the recesses 51 and fastened therein by means of fastenings 54. The shafts 48 and 49 are provided with stub shafts 55 which project from the ends thereof and which are eccentrically disposed relatively to the shafts 48 and 49 and which are journaled at their free ends in openings 56 in the plates 53. The shafts 48 and 49 are also provided with shorter stub shafts 57 which project from the ends of the shafts 48 and 49 and which are substantially smaller in diameter than the stub shafts 55.

The plates 53, at their outer ends, are provided with notches or recesses 58, as seen in Figure 7, in which are disposed the ends of the lower clamping member 36. The ends of the section 39 of the lower clamping member 36 are provided with transverse slot-like openings 59 to loosely receive projections 60, forming a part of the plates 53 and which are hook-shaped and extend into the notches or recesses 58 to loosely engage in the openings 59 of the section 39, as shown in Figures 7 and 8. The inner longitudinal edge 61 of the section 39 of the lower clamping member 36 is provided with a plurality of ears 62 which project therefrom upwardly into the recesses 44. As seen in Figure 8, an ear 62 projects from the edge 61 of the lower section 39 adjacent each end thereof. The complementary longitudinal edge of the lower fixed clamping section 38 is provided with recesses 63 to accommodate the ears 62. A link 64 is pivotally connected to a stub shaft 57 at each end of the shaft 48. The links 64 are pivotally connected to the stub shafts 57 at their upper ends and are pivotally connected, as seen at 65 at their opposite, lower ends to the free ends of the ears 62. A plate 66 is disposed over the lower end of each of the plates 53 and is attached thereto by one of the fastenings 54. The plates 66 are recessed at their lower ends as seen at 67 to fit around the ends of the lower clamping member 36. Plates 66 are provided with extensions 68 which project into their recessed portions 67 and which are provided with arcuately shaped heads 69 which are disposed in the ends of the lower clamping member 36 to form a guide for said ends. Extensions 68 have restricted shanks 69 which extend through recessed portions 70 in the ends of the lower clamping section 38.

The upper clamping member 37 is of identical construction with the lower clamping member 36. The recesses 52 contain inner plates 71, corresponding to the plates 53 and outer plates 72 corresponding to the plates 66 which plates are attached to one another and secured in the recesses 52 by fastenings 73. The plates 71 are provided with notches 58 and hook shaped portions 60 for the same purpose as the similarly designated parts of the plates 53 and the plates 72 are provided with recessed portions 67 and extensions 68, for the same purpose as the similarly designated portions of the plates 66.

Perpendicular bores 74 extend through the rail 34, the rails 50 and portions of the rail 33. The upper ends of the bores 74 open into the upper channel 35, adjacent the ends thereof,

and the lower ends of the bore 74 open into the recesses 45. A link 75 extends loosely through each of the bores 74. Links 75 are pivotally connected at their lower ends to the stub shafts 57 of the shaft 49 and are pivotally connected at their upper ends at 65 to the free ends of the ears 62 of the upper movable clamping member 39 in the same manner that the links 64 are connected to the ears 62 of the lower clamping section 39. As seen in Figure 8, ears 62 of the upper clamping section 39 extend into the upper ends of the bore 74.

Referring to Figures 3 and 8, the shafts 48 and 49, intermediate of their ends, are provided with transverse openings 76 through which loosely extend the restricted shanks of headed pin 77 which pins serve as handles and are disposed in the recess 41 with their headed ends projecting toward the open side thereof. The rail 33 is provided with recesses 78 which extend through the lining 42 and which open into the recess 41. The recesses 78 are disposed in alignment with the openings 76 when said openings are in a horizontal position, as seen in Figure 3. When thus disposed, the pins may be projected inwardly of the shafts 48 and 49 so that their shank ends will engage in the recesses 78 to form latches therewith to prevent the shafts 48 and 49 from turning to thereby retain the clamping members 36 in closed positions. Similar recesses 79 are formed at the top and bottom of the recess 41 for receiving the shank ends of the pins 77 when the openings 76 are inclined inwardly and upwardly of the recess 41 for latching the shafts 48 and 49 in positions, not shown, for holding the clamping members 36 in open positions, not shown.

Assuming that the sashes 16 and 17 are mounted for sliding movement vertically in the frame 11, it will be readily apparent that the upper sash 17 will operate in a conventional manner and will be maintained in any position to which it is moved by the sash weights 18. The inner, lower sash 16 is not provided with sash weights for supporting it in a raised position. However, the spring of the upper roller 28 is intended to be sufficiently strong to maintain the inner lower sash 16 in a raised position when the upper strip of screen fabric 29 is attached thereto, as seen in Figure 3.

The operation of the clamping members 36 and 37 is the same and the description herein-after given of the operation of the lower clamping member 36 will therefore serve as a description of the operation of the upper clamping member 37. As seen in Figure 9, the lower clamping member 36 is shown in a closed position with the outer edges 80 and 81 in close proximity and with the shaft portions 55 and 57 disposed in substantially horizontal planes relatively to one another. In order to open the lower clamping member 36, the pin 76 of the shaft 48 is retracted outwardly, after having opened the door 43 to thereby release the shank end of the pin 77 from its recess 78. Pin 77 is then swung upwardly to turn the shaft 48 in a counterclockwise direction, as seen in Figure 9, to cause the link 64 to be moved downwardly to thereby force the ears 62 downwardly. As the lower clamping section 39 will be prevented from moving outwardly of the lower channel 35 by engagement of the hooks 60 with the slots or openings 59, it will be readily apparent that the upper portions of the slots 59 and the hooks 60 will form pivots on which said section 39 will

swing so that the ears 62 can swing downwardly and partially into the recesses 63 thus causing the lower longitudinal edge 81 to swing in a direction away from the complementary edge 80. 5 to open the lower clamping member sufficiently so that the rod 32 can pass readily thereinto. When the shaft 48 is thus turned in a clockwise direction to the limit of its movement as permitted by the links 64 and connected ears 62, 10 its pin 76 can be projected inwardly to engage the lower recess 79 for thereby latching the lower clamping member 36 in an open position so that it will not engage the rod 32. The upper clamping member 37 can be opened in a like 15 manner by retracting the pin 76 of the shaft 49 and swinging said pin downwardly for turning the shaft 49 in a clockwise direction, as seen in Figure 9, and said pin can also be projected to engage the upper recess 78 for latching the 20 clamping member 37 in an open position.

In order to move the sash 16 to a fully lowered position, when the clamping member 36 is not in engagement with the rod 32, it is essential that said clamping member be open since when the 25 sash is in its fully lowered position the rod 32 must be disposed in the clamping member 36 although not necessarily engaged thereby. Likewise, the upper clamping member 37 must be in an open position in order to move the sash 16 to 30 a fully raised position when the upper rod 31 is not engaged by the clamping member 37.

It will thus be readily apparent that by latching the clamping members 36 and 37 in open positions, as previously described, the sash 16 can 35 be moved to a fully raised or a fully lowered position without interference by the strips 29 or their rods 31 and 32 and by moving the clamping member 36 to a closed position, while the sash is in a lowered position, the rod 32 and the free 40 end of the lower strip 29 will be engaged by the lower end of the sash to be drawn upwardly when the sash 16 is raised. The clamping member 37 can be similarly connected to the rod 31 of the upper strip 29 by moving the sash to a fully 45 raised position and then actuating the operating shaft 49 for closing the clamping member 37.

When the two strips 29 are connected to the ends of the sash 16, it will be readily apparent that when said sash is moved downwardly the 50 upper strip 29 will close the window opening thereabove and when the sash 16 is moved upwardly the lower strip 29 will close the window opening 15 therebeneath so that the upper sash 17 need not be equipped with a window screen. 55 As previously mentioned, the slot-like openings 24 and 25 communicate with the slots 30 to accommodate the longitudinal edges of the screen strips 29 so that they will completely close the portions of the window opening 15 in which they 60 are disposed. As previously mentioned, the spring of the upper roller 28 is intended to be sufficiently strong so that it will support the sash 16 in a raised position even when the lower screen 29 is attached to the clamping member 36.

65 Various modifications and changes are contemplated and may obviously be resorted to, provided they fall within the spirit and scope of the invention as hereinafter defined by the appended claims, as only a preferred embodiment of the 70 invention has been disclosed.

I claim as my invention:

1. Roller type screens mountable respectively at the upper and lower part of a window opening and having their free ends extending into the 75 window opening, a sash slidably mounted in the

window frame opening, clamping members mounted in the end rails of the sash, operating means disposed in one rail of said sash, means connecting said operating means to said clamping members, and said operating means being operable to independently open or close said clamping members, the free end of the mesh wire fabric of the sill being disposed within the clamping member of the lower rail, when said clamping member is opened and when the sash is in its lowermost position, and the free end of the other sheet of mesh wire fabric being similarly disposed relatively to the other clamping member, when said last mentioned clamping member is opened and the sash is in its uppermost position, so that the free ends of each of said sheets of mesh wire fabric may be readily attached to or detached from said sliding sash, said operating means including shafts extending through the bottom rail of the sash and journaled therein, links eccentrically connected to said shafts at adjacent ends of said links, and the opposite, remote ends of said links being pivotally connected to portions of the two clamping members for actuating said portions, when the shafts are turned, for opening and closing the clamping members.

2. Roller type screens mountable respectively at the upper and lower part of a window opening and having their free ends extending into the window opening, a sash slidably mounted in the window frame opening, clamping members mounted in the end rails of the sash, operating means disposed in one rail of said sash, means connecting said operating means to said clamping members, and said operating means being operable to independently open or close said clamping members, the free end of the mesh wire fabric of the sill being disposed within the clamping member of the lower rail, when said clamping member is opened and when the sash is in its lowermost position, and the free end of the other sheet of mesh wire fabric being similarly disposed relatively to the other clamping member, when said last-mentioned clamping member is opened and the sash is in its uppermost position, so that the free ends of each of said sheets of mesh wire fabric may be readily attached to or detached from said sliding sash, the bottom rail of said sash being provided with a recess opening outwardly of one side thereof, said operating means including shafts extending through said recess and journaled in said rail, and handle members for turning said shafts, said handle members being slidably mounted in said shafts, transversely thereof, and said bottom rail being provided with recesses into and out of which said handle members are movable for latching the clamping members in open or closed positions.

3. Roller type strip of mesh wire fabric, the free ends of which are extendable into the top and bottom of the window opening, and a sash

slidably mounted in the window opening, clamping members mounted in the outer edges of the top and bottom rails of the sash and recessed therein, said clamping members each being tubular in shape and being divided longitudinally into sections, each substantially semi-circular in cross section, one section of each clamping member being fixed to the sash, the other section of each clamping member being movably mounted, means carried by the sash for slidably engaging and supporting said movable sections, and means operable manually from one side of the sash for independently actuating said movable sections for opening and closing the clamping members for disengaging them from or engaging them with, respectively, the free ends of the mesh wire fabric strips, said operating means including shafts journaled in one rail of the sash, links eccentrically connected to said shafts at adjacent ends of the links, and the opposite ends of the links being pivotally connected to portions of the movable clamping sections for actuating said movable sections.

4. Roller type strip of mesh wire fabric, the free ends of which are extendable into the top and bottom of the window opening, and a sash slidably mounted in the window opening, clamping members mounted in the outer edges of the top and bottom rails of the sash and recessed therein, said clamping members each being tubular in shape and being divided longitudinally into sections, each substantially semi-circular in cross section, one section of each clamping member being fixed to the sash, the other section of each clamping member being movably mounted, means carried by the sash for slidably engaging and supporting said movable sections, and means operable manually from one side of the sash for independently actuating said movable sections for opening and closing the clamping members for disengaging them from or engaging them with, respectively, the free ends of the mesh wire fabric strips, said operating means including shafts journaled in one rail of the sash, links eccentrically connected to said shafts at adjacent ends of the links, and the opposite ends of the links being pivotally connected to portions of the movable clamping sections for actuating said movable sections, the sash rail in which said shafts are disposed being provided with a recess opening outwardly of one side thereof and through which the shafts extend, and latch means slidably connected to said shafts and disposed in said recess, said latch members being movable manually, with the shafts for opening and closing the clamping members and being manually movable relatively to the shafts for latching the shafts in adjusted positions to hold said clamping members in either open or closed positions.

NELSON B. JOYNER.
